Sigmund Herzog ATTORNEY

UNITED STATES PATENT OFFICE

MOSE E. BLUMENFELD, OF SAVANNAH, GEORGIA

RUBBER SPONGE

Application filed July 17, 1930. Serial No. 468,539.

The present invention relates to a cleaning or scrubbing implement of the rubber-sponge type.

Rubber-sponges are today in general use for cleaning or removal of foreign material, and take the place of the more expensive natural sponges. One of the difficulties experienced in using rubber-sponges for the purpose stated is that there is undue friction 10 created between the surface to be cleaned and the working surface of the sponge when the said working surface is either dry or charged with plain water. Under certain circumstances there is no serious objection to 15 the undue friction above referred to, but it will be readily seen that, when painted or polished surfaces are to be cleaned, the rubber sponges as heretofore manufactured cannot be used, so that natural sponges are being 20 used for cleaning painted or polished surfaces either dry or with plain water.

The main object of the present invention is to provide a composite rubber-sponge, the working surfaces of which are composed of 25 strands of cord or yarn or equivalent strips of woven or other fabric, which are absorbent and serve to reduce the friction between the body portion of the sponge and the surface to which they are to be applied for the purpose of cleaning the same.

Another object of the invention is to provide a composite sponge of the character mentioned which is simple in construction, efficient in operation, durable in use and capable 30 of manufacture on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, 40 pointed out in the appended claims and illustrated in the accompanying drawings, it being understood that many changes may be made in the size and proportion of the several parts and details of construction within 45 the scope of the appended claims, without de-

parting from the spirit or sacrificing any of the advantages of the invention.

Two of the many possible embodiments of the invention are illustrated in the accompanying drawings, in which:—

Figure 1 is an elevation, partly in section, of a rubber-sponge constructed in accordance with the present invention; and Fig. 2 is an elevation, partly in section, of a modification of the invention.

Referring now first to Fig. 1 of the drawings, the numeral 10 indicates a rubber-sponge of any suitable size and configuration, consisting of a spongy mass having many canals or openings extending therethrough 65 for the circulation of the cleaning fluid. In this sponge are embedded fibrous strands of cords or yarns 11, according to the requirements, the free ends of the said cords or yarns, denoted by the numeral 12, extending freely 70 beyond the surfaces of the sponge and forming a mass which loosely covers the sponge surfaces. These free ends are, in the use of the implement, entangled or felted into a mat, so that the sponge is converted into a cleaning implement having a working face in the 75 nature of a fabric. Therefore, obviously, the friction between the surface to be cleaned and the rubber-sponge is materially reduced and the disadvantages of the rubber-sponges over 80 natural sponges entirely overcome.

It is obvious that for scrubbing or rough work rubber-sponges may be used in which coarse cords are embedded, while for finer work yarn of any suitable material may be 85 embedded therein in the manner above described.

The modification illustrated in Fig. 2 of the drawings differs from the one above described in that the rubber-sponge 10 is enclosed in a woven or other fabric 13. The means for uniting the two elements may be of any suitable character, without departing 90 from the invention.

In case the improved rubber-sponge is to be used for applying polish, wax or the like to a surface, it is treated with the material to be applied. In such case, however, the modification illustrated in Fig. 2 of the drawings 95 is preferable, because of the fact that the 100

fabric covering prevents the polish, wax or the like from leaving too freely the sponge.

What I claim is:—

1. A cleaning implement comprising a rubber-sponge body, and spun fibers embedded therein having their ends projecting beyond the surface of said body.
- 5 2. A cleaning implement comprising a rubber-sponge body, and spun fibers embedded therein projecting beyond the surface of said body.

Signed at New York city, in the county of New York, and State of New York, this 14th day of June, A. D. 1930.

15 **MOSE E. BLUMENFELD.**
